UNITED STATES PATENT OFFICE.

CHARLES J. GOFF AND ELMER B. HURSY, OF CLARKSBURG, W. VA.

IMPROVEMENT IN MACHINES FOR CANCELING STAMPS.

Specification forming part of Letters Patent No. 147,630, dated February 17, 1874; application filed November 1, 1873.

To all whom it may concern:

Be it known that we, CHARLES J. GOFF and ELMER B. HURSY, of Clarksburg, in the county of Harrison and State of West Virginia, have invented a new and Improved Machine for Canceling Stamps; and we do hereby declare that the following is a full, clear, and exact description of the same, reference being had to the accompanying drawing, forming a part of this specification, in which—

Figure 1 is a side elevation; Fig. 2, an end view; Figs. 3 and 4, detail views of canceling-rollers.

The invention relates to mechanical means, whereby stamped letter-envelopes and un-stamped circular envelopes in the Post-Office Department may be conveniently and rapidly canceled.

It will first be fully described, and then pointed out in the claims.

A A represent the sills, and B B the side uprights, of a canceling-machine. C is a roll that supports the letter or circular when passing between it and a superposed canceling-roll, D. The latter has a recess, d, in which is inserted (within the die for letter or circular's local point or departure) the date on which the same was received. d¹ is a hole parallel to the axis of roll, that opens into the recess d, and in which works a clamp-screw, E. A hole, b, in upright B allows the introduction of a screw-driver, either to tighten up or loosen the type, which are, of course, to be changed daily. The roll D has surfaces d² d³, which bite on the letter or circular, causing it to pass evenly through, and also a surface-die, d⁴, which makes a cancellation-mark on a letter or circular, upon the latter of which the postage is prepaid without the attachment of a stamp. F is a front inclined guide, that allows the letters to be fed rapidly to the machine, their own gravity carrying them down until the rolls C D bite on them, and transfer them to the other side.

Here they slide down a second inclined guide, G. G' is a plate that holds down the part of the letter or circular that has not yet entered the space between rolls. The supporting-roll C is itself supported upon springs H H, so as to give a yielding pressure upon the letter or circular, while, in order to take up any loss of tension, or any wear in the journal e, or the bearing e', we end-slot this bearing, making it wedge-shaped, and holding it to the journal by clamp-screws e² e². I is the inking-roll, which receives its supply from the distributor J and ink-receiver K. These rolls, together with the canceling-rolls C D, are each provided with an end pulley, partially around each of which passes an endless belt, that may be operated from the drive-pulley of a sewing-machine, or any other small power mechanism.

In order to cause the inking-roll I to always contact evenly and uniformly with the canceler D, we place its journals, after they have passed through two vertical slots in uprights B B, in two levers, N N, and use an adjustable stop, O, and button P to hold the levers at different points of adjustment.

By this machine, a single person will in a comparatively short space of time do all the canceling required at any post-office.

Having thus described our invention, what we claim as new, and desire to secure by Letters Patent, is—

1. The spring H and wedge e', combined with journals e e', passing through slots or uprights B B, as and for the purpose specified.

2. The slotted lever N, stop O, and button P, combined with an inking-roll, I, having its journals in slots of the uprights B B, as and for the purpose described.

C. J. GOFF.
E. B. HURSY.
